TURNTABLE DRIVEN RECORDING MECHANISM

Milford E. Collins, Los Angeles, Calif., assignor to
Radio Corporation of America, a corporation of
Delaware

Application October 31, 1939, Serial No. 302,175

10 Claims. (Cl. 74—411)

This invention relates to sound recording apparatus and particularly to a disc record cutter driving mechanism.

In the art of wax and acetate sound recording, one of the preferred methods of progressively shifting the cutter radially across the wax or acetate disc is by a lead screw rotated from the turntable spindle or the turntable itself. One end of the lead screw is usually attached adjacent the rim of the turntable in a manner such that the other end of the lead screw may be swung over the spindle for connection thereto or swung to one side for the removal of the record. This particular type of mechanism is preferable for instantaneous sound recorders utilizing acetate discs for immediate reproduction. The cutter head for acetate discs imposes upon the lead screw and prime mover considerable load, since the material being cut is of a heavier composition than the usual recording wax. Furthermore, as the axis of the lead screw is in a plane parallel to the plane of the turntable, the connection between the lead screw and the turntable or spindle is made through a countershaft geared to the lead screw at one end and positively connected to the other end of the turntable spindle or frictionally connected to the record disc on the turntable which supports the lead screw assembly.

It has been found preferable to positively drive the lead screw so that a definite angular relationship exists at all times between the revolutions of the record on the turntable and the lead screw. This produces a more uniform pitch and width to the grooves being cut. Also, to maintain the proper frequency of the produced sounds, it is desirable that the turntable and record blank rotate at a constant speed. To aid in obtaining this constant speed, mechanical filters and fly-wheels are provided between the prime mover and the turntable. However, variations in load on the cutter, caused by a binding action at any point in the mechanism will tend to create variations in turntable speed.

In this type of sound recorder, provision must be made for the ready connection of the turntable spindle with the lead screw so that the record cutter may be quickly placed in position for operation and quickly removed after the record is cut. In the present invention, this is accomplished by providing a flat-sided or square-shanked spindle and the shaft connecting the lead screw with the flat-sided spindle, with a socket containing a resiliently mounted broached member which accommodates the shank of the spindle. There is thus provided a constant ratio

between the turntable rotations and the rotations of the lead screw. In such a connection, however, it is difficult, in commercial manufacture, to make the flat-sided or square-shank of the spindle and the accommodating aperture so perfect that there will be no irregularities in the connection therebetween for the different angular positions at which connection may be made. It is also difficult, in commercial manufacture, to prevent slight eccentricities occurring in the rotation of the turntable and spindle. Such discrepancies and eccentricities generally produce a periodic binding action between the driven shaft and spindle such as to similarly vary the load on a prime mover. Because of the flexibility of the mechanical filter, these variations in load introduce what are commonly called "wows," or a "once-or-twice-around" distortion in the cut record. This, of course, is detrimental to good recording. The present invention is thus directed to a simple and efficient connecting unit for preventing variations in load or other irregularities in the connecting mechanism from affecting the recording.

The principal object of the invention, therefore, is to improve sound-on-disc recording.

A further object of the invention is to provide a connection between a driving and a driven element connectable in several different angular relationships which will be uniform at all times regardless of discrepancies in the different angular connection relationships.

A further object of the invention is to provide a positive connection between a turntable spindle and a disc cutter lead screw which will equalize the load on the prime mover for different angular connections between the spindle and lead screw.

A further object of the invention is to provide a spindle driven cutter lead screw connecting mechanism which will compensate for minor irregularities at one point and for greater irregularities at a second point.

Although the novel features which are believed to be characteristic of this invention will be pointed out with particularity in the claims appended herewith, the invention itself, its objects and advantages, the manner of its organization and the mode of its operation will be better understood by referring to the following description read in conjunction with the accompanying drawing forming a part thereof, in which

Figure 1 is a front elevational view of a sound-on-disc recorder embodying the invention;

Figure 2 is a cross-sectional view of the con-

necting mechanism between the turntable spindle and the lead screw assembly taken along the line 2—2 of Fig. 1;

Figure 3 is a detailed sectional view of the connecting mechanism taken along the line 3—3 of Fig. 2;

Figure 4 is a cross-sectional view of the mounting support for the lead screw assembly taken along the line 4—4 of Fig. 1; and

Figure 5 is a detailed view of the mounting shown in Fig. 4 taken along the line 5—5 of Fig. 4.

Referring now to the drawing in which like elements have been given identical numerals, a turntable 5 having a felt or similar top covering 6 is mounted upon a support 3 to which is bolted its bearing housing 8. The turntable is driven from a prime mover such as a motor 10 through a reduction gear box 11, a mechanical filter 12, a shaft 13 and a coupler 14. A flywheel 15 is mounted on the upper drive shaft for stabilizing the rotation of the turntable. A record 20 is cut by the stylus of a cutter head 18 mounted on an assembly 19 which, in turn, is moved radially across the record 20 by means of a lead screw 22. The lead screw 22 is mounted on a bracket 25, one end of which is rotatable upon a conical bearing 26, and the other end of which is rotatable in a bearing 27.

The lead screw 22 is geared to a vertical shaft 28 within a housing 30 of the bracket 25 (see Fig. 2). The shaft 28 is enlarged at the lower end thereof to form a socket or thimble 32 to which is fastened, by screws 33, a flanged disc 34 having a resilient pad 36 such as rubber or felt on the underside thereof. The shaft 28 has mounted thereon a gear 38 rotatable in a bearing member 39, the gear 38 meshing with a gear 40 on the lead screw 22.

The turntable 5 has a square-shanked spindle 41 either integral with the turntable or affixed thereto, and is shown in Fig. 2 inserted within the broached aperture of a cylindrical member 42. Between the member 42 and the interior of socket 32 is shown a rubber bushing 44, which bushing is firmly attached to both the inner wall of the thimble 32 and the outer surface of the member 42 by vulcanizing or in other like manner. A clearance is provided between the disc 34 and the member 42 to permit the member 42 to twist should the spindle 41 have an eccentric motion, or to be slightly bodily translated should one position of connection between spindle 41 and member 42 bind in a particular direction. Furthermore, should the surface of the turntable 5 not rotate in a single plane or in a plane not parallel to the plane of the axis of lead screw 22, the resilience of the pad 36 will not shift the axis of rotation of shaft 28.

In the above mechanism just described, it will be noted that, because of the flat-sided spindle and its connecting element, there is a positive angular relationship between the rotation of the turntable 5 and the lead screw 22 which drives the cutter head 18. This is a particularly desirable feature. Furthermore, to aid in making the connection, the shank 41 has a square cross-section so that connection may be made in at least four different angular positions. The novel construction of the connecting unit, however, permits any of these angular connections to be made without affecting the recording should any binding action or other irregularity exist for any of the angular positions in which connection is

made. Thus, greater tolerances are provided for the manufacture of the apparatus.

It sometimes occurs in the commercial operation of the above-described apparatus that the turntable spindle 41 or turntable has considerable eccentricity, such that the coupling unit described above is insufficient to compensate therefor. The result is a binding action between the lead screw assembly and the spindle. To prevent this binding action, a provision has been made to permit the entire lead screw assembly to be bodily translated along the axis of the lead screw by a special mounting of the assembly as shown in Figs. 4 and 5.

In Fig. 4 is shown an enlarged housing portion 46 of the bracket 25 with a set screw 47 therein for the adjustment of the conical bearing 26. The housing 46 is mounted to permit the vertical movement of the spindle and of the lead screw 22 by providing two conical bearings 49 carried by the ends of a yoke 50, the yoke having an axle 51 to permit rotation of the lead screw assembly. This end of the lead screw may be adjusted as to height by means of a set screw 53 passing through a bearing sleeve 54 and a sleeve 55 and contacting the axle 51 in a groove 56. The sleeve 54 has a circular flange 57, this flange resting upon a circular washer bearing 58 attached to the mounting board 3 by means of screws, one of which is shown at 60. The flange 57 is overlaid with a circular washer 61 and slightly spaced from the upper surface of flange 57 by a shoulder portion 59 of the bearing 58. The bearing 58 and washer 61 are affixed to one another by means of screws, one of which is shown at 62. The flange 57 is loosely held between the washer 61 and the bearing 58, while provision is made for a lateral movement of the axle 51 by making the outside diameter of the flange 57 smaller than the internal diameter of the shoulder portion 59. To accommodate this movement, the internal diameter of the washer 61 is larger than the external diameter of sleeve 54. By this interleaving of the flange 57 and washers 58 and 61, the sleeve 54, axle 51 and entire lead screw assembly may be translated horizontally in accordance with the lateral pressure on the assembly by bodily movement of the spindle 41. Thus, any binding action at the spindle is relieved, preventing variations in load on the motor.

From the above description, it will be observed that to avoid the deleterious effects of minor eccentricities or irregularities in the connection between the spindle 41 and the shaft 28, the coupling unit 32, 42 and 44 is provided. Should the irregularities or eccentricities be too large for this unit to accommodate, the mounting in Figs. 4 and 5 permits the entire lead screw assembly to be bodily moved along the axis of the lead screw to prevent these discrepancies from interfering with recording. If the spindle coupling unit is rather stiff, both the spindle unit and the assembly mounting may function simultaneously to provide a uniform motor load.

What I claim as my invention is:

1. In combination, a lead screw adapted to be driven from a spindle having an axis at right angles to the axis of said lead screw, said spindle having eccentricities in the rotation thereof, means for positively connecting said spindle and said lead screw in a plurality of predetermined angular relationships, said means including a shaft, a gear thereon, and a gear on said lead screw meshing with said shaft gear, means in-

cluded in said connecting means for compensating for small eccentricities of said spindle, and means at the other end of said lead screw for compensating for larger eccentricities of said spindle.

2. In combination, a lead screw having a fixed mounting at one end thereof and a movable mounting at the other end thereof, a driving spindle having a square shank, means for connecting said screw to said spindle about said shank, said means including a gear on said lead screw meshing with a gear driven by said spindle, means for compensating for small irregularities of said shank, and means included in said fixed mounting for compensating for larger irregularities of said spindle.

3. A combination in accordance with claim 2 in which said first-mentioned compensation means comprises a member having a square opening to accommodate said shank and a resilient bushing surrounding said member for transmitting rotation of said member to said screw.

4. A combination in accordance with claim 2 in which said second-mentioned compensation means comprises a bearing rotatable and slidable in a plane parallel to the plane of said turntable.

5. A sound recording system comprising a turntable, means for rotating said turntable, a spindle at the center of said turntable, a lead screw one end of said lead screw being mounted adjacent the rim of said turntable, and the other end of said lead screw being adapted to be connected to said spindle in a plurality of predetermined angular relationships, means for connecting said spindle and said lead screw, said means including a gear on said lead screw meshing with a gear driven by said spindle, means for equalizing small irregularities in rotation of said spindle, and means included in said mounting means for equalizing large irregularities in said connecting means.

6. A sound recording system in accordance with claim 5 in which said connecting means includes a square shank for said spindle, a shaft having a socket containing a broached cylinder adapted to accommodate said shank, and a resilient bushing attached to said cylinder intermediate said cylinder and said shaft.

7. A mechanism for a sound recording device comprising a turntable, a spindle on said turntable having a square shank adapted to be rotated with said turntable, a shaft adapted to be periodically positioned in coaxial alignment with said spindle and supported by said turntable, said shaft having an enlarged thimble portion, a cylindrical member within said thimble portion, said member having a square aperture adapted to accommodate said shank in a plurality of predetermined angular positions, and a resilient member interposed between said member and the interior of said thimble to prevent small eccentricities in rotation of said spindle and turntable from being transmitted to said shaft, and means at the other end of said shaft for preventing larger eccentricities in rotation of said spindle and turntable from varying the load on said spindle.

20 8. A mechanism in accordance with claim 7 in which said resilient member is vulcanized to the members contacted thereby.

9. A lead screw mechanism for a sound recorder comprising a turntable, a spindle for said turntable and adapted to be rotated therewith, said spindle and turntable being subject to eccentricities in rotation, a horizontally disposed lead screw having one end translatable about a fixed mounting, a gear on said lead screw, a vertically disposed shaft for rotating said screw, a gear on said shaft meshing with said lead screw gear, means for resiliently connecting said spindle to said shaft in a plurality of predetermined angular positions, said connecting means insulating said screw from small eccentricities in rotation of said spindle and turntable, and means for permitting longitudinal translation of said lead screw along the rotational axis thereof to accommodate larger eccentricities in rotation of said spindle and turntable.

40 10. A lead screw mechanism in accordance with claim 9 in which said last-mentioned means includes an interleaved bearing having a clearance between the outer and inner diameters of 45 leaves in the same plane.
